His Attorney.

UNITED STATES PATENT OFFICE

CHARLES F. CARPENTER, OF SCHENECTADY, NEW YORK, ASSIGNOR TO GENERAL ELECTRIC COMPANY, A CORPORATION OF NEW YORK

ELECTRIC SWITCH

Application filed April 27, 1928. Serial No. 273,877.

My invention relates to electric switches, more particularly to reversing switches, and has for its object the provision of an operating mechanism therefor, which is of simple construction, and durable, effective and convenient in operation.

Where motors are frequently reversed, reversing switches are provided as a part of the motor controller in order that the direction of rotation of the motor may be reversed as desired. Such reversing switches are provided with a set of forward contacts which when interengaged permit a flow of current in the proper direction for forward motion of the motor, and with a set of reverse contacts which when interengaged permit a flow of current in the proper direction for reverse motion of the motor. Although such reversing switches may be manually operated, frequently power actuated means, as for example, electromagnets are provided for operating the switch, particularly in those cases where frequent reversing of the motor is necessary and also in those cases where the reversing switch comprises a number of contacts for both forward and reverse motion.

In either the case of manual operation or that of power operation it is very necessary when either set of contacts has been moved into engagement that they be securely held in that position until it is desired to stop the motor. Thus, it is desirable that the operating means be employed merely to move the contacts into engagement and that suitable locking means be provided for holding them in engagement after they have been so moved. My invention therefore contemplates the provision of locking means for a reversing switch which operates to securely maintain either set of the switch contacts in engagement after they have been so moved by the actuating means.

In carrying my invention into effect in one form thereof, I provide a latch operably associated with the moving contacts so that when they have been moved into engagement with their corresponding stationary contacts they are positively locked in their engaging position until the latch has been re-

leased. I further provide releasing means for the latch so that the contacts may be disengaged.

For a more complete understanding of my invention reference should be had to the accompanying drawings in which; Fig. 1 is a diagrammatic representation of a power actuated reversing switch provided with latching means in accordance with my invention, and Fig. 2 is a detailed view of portions of the power actuating and latching means.

Referring to the drawings, I have shown my invention in one form as applied to a power actuated reversing switch provided for reversing the direction of motion of an alternating current motor. As shown, a suitable reversing switch 10 is provided for reversing the current flow from the source 11 through the alternating current motor 12 so that its direction of rotation may be reversed. The reversing switch 10 comprises three forward stationary contacts 13 and three reverse stationary contacts 14. Suitable movable contacts 13a and 14a are provided for cooperating with the stationary contacts 13 and 14, respectively, whereby the current may be caused to flow in either one direction or the other, as desired. The movable contacts 13a and 14a are mounted upon a rotatable shaft 15, suitable operating means being provided for causing the shaft 15 to rotate in one direction or the other so as to cause interengagement of either set of contacts.

A shaft 16 is mounted in suitable relation to the shaft 15 and operating connecting means between the shafts 15 and 16 are provided whereby when rotatable motion is imparted to the shaft 16 rotatable motion will likewise be transmitted to the shaft 15. To effect this transmission of motion, the shaft 16 is provided with a bell crank 17 one arm 17a of which is connected by means of a link 18 to a rigid arm 19 projecting from the shaft 15. Any suitable means, either manually or power actuated, may be provided for causing the shaft 16 to rotate in one direction or the other, as desired. As shown, electromagnets are provided for this

purpose, the forward electromagnet, that is the magnet for operating the reversing switch to cause the forward contactors 13 and 13a to interengage, is designated by the ordinal 20 and the reversing electromagnet, that is the magnet for causing the reverse contactors 14 and 14a to interengage, is designated by the ordinal 21. The shaft 16 is provided with a rigidly connected rocker arm 22 which is adapted to be actuated by movement of either of the electromagnet armatures 20a or 21a. As shown, each of the electromagnet armatures is weighted and is provided with a depending link 23, the lower end of which is connected to one end of a link 24, the latter being pivoted at its opposite end to a stationary support 25. Each of the links 23 is provided at its lower end with a roller 26, the roller 26 upon being moved upwardly engaging a cam surface 27 provided on the rocker arm 22. Thus, it will be observed upon upward motion being imparted to either of the links 23, the rocker arm 22 and consequently the shaft 16 will be rotated in one direction or the other, as the case may be. The levers 23 are further provided with projecting pins 28, which pins 28 upon downward movement of the levers engage the upper cam surfaces 29 of the rocker arm 22 so that upon downward motion being imparted to either of the levers 23, the rocker arm 22 will be returned to its horizontal position, as shown in the drawing. The pins 28 also perform the function of supporting the weighted armatures in their elevated positions, the pins 28 resting upon their corresponding cam surfaces 29.

It will be understood that the links 23 are moved upwardly by the armatures 20a and 21a when their corresponding electromagnets are energized, and that at the proper times the links 23 are moved downwardly under the influence of the weighted armatures 20a and 21a, suitable stops 25a being provided on the support 25 for limiting their downward movement.

Suitable latching means is provided for locking the rocker arm 22 in either of its extreme positions, as determined by movement of the armatures, since not only must the contacts be held in intimate engagement but the weighted armatures must be supported. The latching means comprises a latch 30 pivoted at one end to a stationary pin 31. The latch 30 is provided with an abutment 32, the abutment 32 being moved at the proper times into the path of movement of the arm 17b of the bell crank 17 for preventing return movement of the rocker arm 22 after it has been moved in one direction or the other by the electromagnets.

In order that the latch 30 may be securely held in its locking position, shown in Fig. 2,

a toggle 34 is provided, the upper end of the toggle being pivoted to a stationary pin 35. It will be observed when the toggle 34 is broken, as shown in Fig. 1, that the latch 30 is in its elevated position thereby permitting unobstructed movement of the arm 17b, but that when the toggle is aligned, as shown in Fig. 2, the latch 30 is securely locked in its lower position thereby obstructing the path of movement of the arm 17b. Suitable controlling means, shown as electromagnets 36 and 37, are provided for breaking the toggle, and also for allowing the toggle to align itself whereby the latch 31 may be locked in its lower position. The armature 36a of the electromagnet 36 is directly connected to one arm 38a of a bell crank 38, pivotally mounted upon the pin 39, the other arm 38b of the bell crank 38 being provided with an abutment 40, which upon movement of the bell crank 38 in a counter-clockwise direction, as viewed in Fig. 1, engages the toggle 34 to break it. The armature 37a of the electromagnet 37 is pivotally connected to a substantially U-shaped member 42. As shown, the upper arm of the U-shaped member 42 is pivoted to the stationary pin 35, while the lower arm of the U-shaped member 42 is adapted to engage the toggle 34 when the magnet is de-energized whereby the toggle is held in its broken position under the influence of the weight of the armature 37a. It will be observed that when the magnet 37 is energized the U-shaped member 42 will be swung in a counter-clockwise direction, as viewed in Fig. 1, whereby its lower arm will be moved away from the toggle and the toggle permitted to align itself. It will be further observed that when the electromagnet 36 is energized, the bell crank 38 will be moved in a counter-clockwise direction, as viewed in Fig. 1, and the toggle will be broken.

A suitable source of current supply 50 is provided for energizing the electromagnets 20, 21, 36 and 37. Suitable control means are provided whereby the electromagnets may be energized at the proper times. As shown, a suitable forward push button 51 is inserted in a circuit including the coil 20b of the forward electromagnet 20, a reversing push button 52 is inserted in a circuit with the coil 21b of the reversing electromagnet 21, and a stop push button 53 is inserted in a circuit with the coil 36b of the electromagnet 36. Suitable control means are provided whereby the coil 37b of the electromagnet 37 may be energized so that the toggle 34 may align itself immediately after either of the electromagnets 20 or 21 has been energized. As shown, a relay contact 54 is operably connected to the armature 20a of the electromagnet 20 by means of a rod 55, the contact 54 being provided to close a circuit from the source 130

50 through the coil 37b of the electromagnet 37 when the armature 20a has been moved to its upper limit. Likewise a relay contact 57 is operably connected to the armature 21a of the electromagnet 21 by means 5 of a rod 58 so that upon energization of the electromagnet 21, a circuit is completed from the source 50 and through the coil 37b of the electromagnet 37. Thus, should either of the armatures 20a or 21a be moved 10 to and held in its upper position, a circuit through the coil 37b will be closed and the coil energized as long as the armature is so held, whereby the member 42 will be withheld from the path of movement of the 15 toggle 34.

The rod 55 is further provided with a contact 60 for making and breaking a circuit from one side of the source 50 through the 20 coil 21b of the electromagnet 21, and likewise the rod 58 is provided with a contact 61 for making and breaking a circuit from one side of the source 50 through the coil 20b of the electromagnet 20. Thus, when either of the electromagnets 20 or 21 is energized, the contacts 60 or 61, as the case 25 may be, will be elevated so that it is impossible to complete the circuit through the other of the electromagnets by depressing its corresponding push button 51 or 52, thereby rendering it impossible to have both 30 of the electromagnets energized at the same instant. It will be observed that upward movement of the armature of either of the 35 actuating electromagnets 20 or 21 performs three functions, that of causing interengagement of either the forward or reverse switch contacts, that of completing a circuit through the coil 37c of the electromagnet 37, and that 40 of preventing energization of the other actuating electromagnet.

The operation of the reversing switch is as follows: Assuming the parts to be in their positions as shown in Fig. 1, it will be observed that the reversing switch 10 is in its neutral position, neither the forward or the 45 reversing contacts being in engagement. It will be further observed that the toggle 34 is held in its broken position and the latch 30 is elevated since the electromagnet 37 is deenergized. Thus, unobstructed movement 50 of the bell crank 17, and consequently of the rocker arm 22, is possible. Assuming that it is desired to operate the motor 12 in a forward direction, the forward push button 51 is depressed, thereby completing a circuit from one side of the source 50 through the push button 51, the contacts 61, and the coil 20b of the 55 electromagnet 20 back to the other side of the source. The armature 20a of the electromagnet 20 will then be raised to its upward position, pulling the link 23 upwardly with it. As the link 23 so moves, the roller 26 engages the cam surface 27 of the rocker arm 60 65 70 75 80 85 90 95 100 105 110 115 120 125 130

22, thereby moving the arm 22, the shaft 16 and the bell crank 17 in a counter-clockwise direction, as viewed in Fig. 1. As the bell crank 17 so moves, the shaft 15 is likewise moved and the movable contacts 13a are moved into engagement with their stationary contacts 13, whereby the motor is energized to run in a forward direction. When the armature 20a has moved completely to its upper position, the arm 17b of the bell crank 17 will be moved to a point at which when the latch 30 is allowed to move to its lower position it will be locked against return movement by the abutment 32; the contact 54 will complete the circuit from the source 50 through the coil 37b of the electromagnet 37 whereby the toggle is permitted to align itself and the latch 30 is moved into its locking position; and the contact 60 will be elevated whereby it will be impossible to energize the reverse electromagnet 21. Thus it will be observed that it is only necessary to temporarily depress the button 51 to cause the forward contactors 13 and 13a to be moved into engagement with each other; to cause the latch 30 to be moved into its locking position; and to prevent any possible attempt to complete a circuit from the source 50 and through the electromagnet 21.

Should it be desired to stop the motor 12, the stop push button 53 is depressed, thereby completing a circuit from one side of the source 50, through the button 53 and the coil 36b of the electromagnet 36 to the other side of the source 50 whereby the armature 36a is raised to its upward position and the bell crank 38 swung about its stationary pivot to break the toggle. As soon as the toggle 34 is broken and latch 30 raised so that the abutment 32 is moved upwardly out of the path of movement of the arm 17b of the bell crank 17, the rocker arm 22 will be moved under the influence of the weighted armature 20a to its horizontal position, shown in Fig. 1, since the pin 28 carried by the link 23 engages the cam 29 of the rocker arm. When the armature 20a is moved downwardly, the contact 54 will be moved to break the circuit through the coil 37b of the electromagnet 37 and the member 42 will be swung into a position to hold the toggle 34 in its broken position. If desired, a centering device of any well known construction may be provided for the shaft 16 whereby the rocker arm 22 may not only be returned to its neutral position by the weighted armatures 20a or 21a but also by the centering device.

The operation of the switch mechanism for causing reverse motion of the motor 12 is identical with that described for causing forward motion. Upon pushing the button 52 a circuit is completed through the coil 21b of the electromagnet 21 and the armature 21a and its connected link 23 are moved up-

wardly to cause the rocker arm 22 to move in a clockwise direction, as viewed in Fig. 1. Thus the movable contacts 14a are caused to engage their corresponding stationary contacts 14. The arm 17b will be locked in its extreme reverse position by the abutment 32 until the stop push button 53 is again depressed and the toggle 34 broken; the electromagnet 37 will be energized so that the member 42 will be withheld from the toggle 34; and the contact 61 will be raised to a position whereby any attempt to complete a circuit through the forward electromagnet 20 will be defeated.

15 While I have described my invention as embodied in concrete form and as operating in a specific manner in accordance with the provisions of the patent statutes, it should be understood that I do not limit 20 my invention thereto since various modifications thereof will suggest themselves to those skilled in the art without departing from the spirit of my invention the scope of which is set forth in the annexed claims.

25 What I claim as new and desire to secure by Letters Patent of the United States, is:—

1. A switch comprising two sets of stationary contacts, two sets of normally open movable contacts for cooperating therewith, 30 operating means connected to said contacts whereby either of said sets may be moved into interengagement, a latch operably connected to said movable contacts so as to lock either set thereof in its position of interengagement with the stationary contacts, and releasing means for either of said contacts operably connected to said latch.

2. A switch comprising a pair of cooperating contacts, operating means connected 40 to said contacts whereby said contacts may be moved into interengagement, a latch adapted to lock said operating means whereby when said contacts have been moved into interengagement return movement 45 thereof is prevented, and means connected to said latch normally maintaining said latch in an unlocking position to prevent unobstructed movement of said operating means, said means being responsive to the 50 movement of said operating means so as to cause said latch to move into its locking position after said interengagement has been effected.

3. A switch comprising two sets of stationary contacts, two sets of movable contacts for cooperating therewith mounted upon a common supporting member, actuating means for said member whereby either 60 set of said movable contacts may be caused to interengage its corresponding set of stationary contacts, a latch operably associated with said member for locking said member in position after interengagement of either 65 of said sets has been effected, and releasing

means for said latch so as to permit disengagement of said contacts.

4. A switch comprising a pair of oppositely disposed stationary contacts, a pair of normally open movable contacts for co-operating therewith, actuating means operably connected to said movable contacts for causing interengagement of either of said movable contacts with its stationary contact, a latch operably associated with said 70 operable connections for locking said connections in position after said interengagement of either of said movable contacts with its stationary contact has been effected so as to prevent disengagement of said contacts, and releasing means for said latch so as to permit disengagement of said contacts. 75

5. A switch comprising a pair of cooperating contacts, operating means connected to said contacts whereby said contacts may be moved into interengagement, a latch adapted to lock said operating means whereby when said contacts have been moved into interengagement return movement 80 thereof is prevented, and an electromagnet operably connected to said latch and normally maintaining said latch in an unlocking position to prevent unobstructed movement of said operating means, said electromagnet being responsive to the movement of said operating means so as to cause said latch to move into its locking position after 85 said interengagement has been effected. 90

6. A switch comprising two sets of cooperating contacts, actuating means operably connected to said contacts whereby either set of contacts may be moved into interengagement, a latch for cooperating with said operable connections whereby when either set of said contacts has been moved into interengagement said actuating means is locked so as to prevent disengagement of said contacts, a toggle operably connected to said latch, and means connected to said toggle normally maintaining said toggle in released position so as to hold said latch in an unlocking position with respect to said operable connections, said means being responsive to the movement of said actuating means whereby when interengagement of said contacts has been effected said toggle is released to allow said latch to move into its locking position. 100 105 110 115

7. A switch comprising two sets of cooperating contacts, actuating electromagnets operably connected to said contacts whereby either set of contacts may be moved into interengagement, a latch for cooperating with said operable connections whereby when either set of said contacts has been moved into interengagement said operable connections are locked so as to prevent disengagement of said contacts, a toggle operably connected to said latch whereby when 120 125 130

- 5 said toggle is released said latch is held in an unlocking position, and an electromagnet connected to said toggle normally deenergized so as to maintain said toggle in its released position, said electromagnet being responsive to movement of the armatures of said actuating magnets whereby when interengagement of said contacts has been effected said electromagnet is energized so as to permit said toggle to move said latch into its locking position.
- 10 8. An electric switch comprising two sets of stationary contacts, two sets of movable contacts for cooperating therewith, a rocker shaft operably connected to said movable contacts whereby upon movement of said shaft in one direction from its neutral position one set of movable contacts is moved into engagement with their stationary contacts and upon movement of said shaft in the other direction from its neutral position the other set of said movable contacts is moved into engagement with their stationary contacts, an arm rigidly mounted upon said shaft, latching mechanism comprising a latch provided with an abutment for cooperating with said arm whereby when said shaft has been moved in either direction to cause interengagement of one set of said contacts said abutment is moved into the path of movement of said arm to prevent return movement of the shaft and said movable contacts, and means for releasing said latching mechanism to permit return movement of said contacts.
- 15 9. A reversing switch for an electric motor comprising a plurality of cooperating contacts for establishing forward and reverse connections, an operating shaft for said contacts, a rocker arm, operable connections between said rocker arm and said shaft whereby upon motion of said arm in one direction from a neutral position said shaft is moved to establish forward connections and upon motion of said arm in the other direction from a neutral position said shaft is moved to establish reverse connections, means for operating said shaft in either direction as desired, a latch cooperating with said operable connections for locking said contacts in position when moved to establish either the forward or the reverse connections, and means for releasing said latch to permit disengagement of said contacts.
- 20 10. A reversing switch for an electric motor comprising a plurality of cooperating contacts for establishing forward and reverse connections, a shaft, a rocker arm rigidly mounted on said shaft and operably connected to said contacts whereby upon motion of said arm in one direction from its neutral position said forward connections are established and upon motion of said arm in the other direction from its neutral position said reverse connections are established, an arm rigidly mounted on said shaft, a latch provided with an abutment cooperating with said arm whereby upon movement of said rocker arm in either direction to a position to establish either forward or reverse connections said abutment is moved into the path of movement of said arm so that said arm, rocker arm and contacts are locked in their contact closing positions, a toggle associated with said latch for locking said latch in said contact closing position, and means for breaking said toggle so as to release said latch to permit said contacts to break said connections.
- 25 11. In combination, a switch member movable between a plurality of positions, means for selectively operating said switch member each way from one position to other positions, locking means including a movable latch for maintaining said switch member in either of said other positions independently of said operating means, and means for controlling said latch so that said latch normally is maintained in its unlocking position to permit movement of said switch member from said one to either of said other positions and is operated responsively to the operation of said operating member so as to lock said switch member in either of its other positions after said switch member has been moved to said other position.
- 30 12. A switch comprising two sets of cooperating contacts, actuating means operably connected to said contacts whereby either set of contacts may be moved into interengagement, a latch for cooperating with said operable connections whereby when either set of said contacts has been moved into interengagement, said operating means is locked so as to prevent disengagement of said contacts, a toggle operably connected to said latch, means connected to said toggle normally maintaining it in released position so as to hold said latch in an unlocking position with respect to said operable connections, said means being responsive to the movement of said actuating means whereby, when interengagement of said contacts has been effected, said toggle is released to allow said latch to move to its locking position, and means for moving said toggle to a position to hold said latch in its unlocking position.
- 35 13. In combination, a switch member movable between a plurality of positions, electrically controlled means for selectively operating the member each way from one position to other positions, electrically controlled means including a movable latch for maintaining said member in either of said other positions independently of the operating means, and manually controllable electroresponsive means for releasing said latch.
- 40 14. In combination, a movable switch

member biased to a position intermediate two other positions, electroresponsive means for selectively operating the member each way from said biased position to a corresponding one of said other positions and an 5 electrically controlled latch for holding the member in either of said other positions independently of the operating means.

15. In combination, a movable switch member biased to a position intermediate two other positions, electroresponsive means for selectively operating the member each way from said biased position to a corresponding one of said other positions, an 15 electrically controlled latch for holding the member in either of said other positions independently of the operating means and releasing means for said latch.

In witness whereof, I have hereunto set
20 my hand this 26th day of April, 1928.
CHARLES F. CARPENTER.
